UNITED STATES PATENT OFFICE.

ARTHUR O. HUBBARD, OF MINNEAPOLIS, MINNESOTA.

BOX.

No. 906,281.

Specification of Letters Patent.

Patented Dec. 8, 1908.

Application filed March 12, 1906. Serial No. 305,521.

To all whom it may concern:

Be it known that I, ARTHUR O. HUBBARD, of Minneapolis, Hennepin county, Minnesota, have invented certain new and useful Im-
5 provements in Boxes, of which the following is a specification.

My invention relates to boxes used for package shipping and delivering purposes, and the object of the invention is to provide
10 a box of economical construction, and one that will be strong and durable, and in the construction of which comparatively thin, inexpensive lumber can be used.

The invention consists, generally, in providing a box having walls composed of comparatively thin narrow strips, and improved means for securing the said strips together to form the panels of the box.

In the accompanying drawings forming part of this specification, Figure 1 is a perspective view of the box embodying my invention. Fig. 2 is a similar view with the top and one side wall removed. Fig. 3 is a detail sectional view illustrating the means employed for securing the parts of the wall panels together. Fig. 4 is a perspective view illustrating the manner of making the sides and bottom of the box in one continuous strip or panel. Fig. 5 is a perspective view illustrating a panel or continuous strip before it is folded to form the walls of the box. Fig. 6 is a detail perspective view showing the grooves provided to receive the binding wire, and Fig. 7 is a sectional view showing the wires fitting within the grooves on each side of the panel and the means for binding the opposite wires together. Fig. 8 is a detail showing means for binding the wires together between the strips.

40 In the drawing, 2 represents the end panels of the box, 3 the sides, 4 the bottom, and 5 the top. The sides, bottom and top are all composed of comparatively thin narrow strips 6 placed edge to edge, and having
45 grooves 7 extending transversely therein near each end entirely around the panel. These grooves, which are for the purpose of partially concealing and protecting the wires and preventing them from being bent
50 or broken by contact with any other object, are of any suitable depth and width varying usually with the size of the box and the purpose for which it is to be used. The panels are preferably provided with the grooves,
55 but I do not confine myself to their use, as the wires, when drawn and embedded by the

staples as described, will perform their functions of holding the strips together, even if the grooves are omitted. In the box shown in Sheet 1 the panels are all formed separately each comprising a suitable number of strips to obtain the desired width of panel.

For the purpose of binding the strips together a wire 8 is laid in each groove extending entirely around the panel and having its ends secured together in any suitable way, as by binding and interlocking them, or by twisting them together on one edge of the panel, as indicated at 9 in Fig. 3. The twisting of the wire ends will draw it taut in the grooves, and for the purpose of binding the opposite parallel leads of the wire together and closing the joints between the strips composing the panel, I provide staples 10 which are forced through the strips on one side straddling the wire on that side, and then have their ends clenched or bent around the wire on the other side thereby forcing the wire into the wood on each side of the panel and forming little offsets or bends 11 in the wire and drawing up or shortening the same to such an extent that the edges of the strips composing the panel will be drawn snugly together and firmly held in that position. I prefer to employ one staple for each strip arranged substantially as shown in Fig. 3, but the number used may be varied according to the width of the strips. When these staples are inserted and locked around the wires, the edges of the strips will be drawn together so snugly that the panels will be as stiff and inflexible as though composed of a single piece, instead of being made up of a number of narrow strips. The end panels are made in the same way and in addition have border strips 12 extending around their edges and bracing and strengthening the same and forming nailing surfaces for the side, top and bottom panels. The strips 12 preferably have mitered interlocking ends, so that neat substantial joints may be formed between the strips at the corners of the panels. The strips composing the end panels will be secured to the strips 12 by nails or other suitable means.

105 In Figs. 4 and 5 I have shown a box composed of panels constructed in the same way, but with the side walls and bottom made in one continuous sheet or panel folded at the corners. The strips are grooved in the same manner on each side, and the wires are fitted therein and stapled, as described with ref-

erence to Fig. 3, the edges of the strips being firmly bound together by the shortening of the wires when the staples are inserted; and each panel, even those of considerable length, can be handled as one board. The panels made in this way can not only be utilized to form the bottom, sides and top of a box, but manufactured of comparatively thin material may serve as a wrapper to protect various articles of merchandise while being shipped from place to place. Boxes of the kind heretofore described are usually manufactured and shipped to the users in knock-down form, being put together at the destination by nailing machines and used extensively for packing and shipping all kinds of merchandise. A box, therefore, which will be of comparatively thin material and of light construction, but capable of considerable rough handling and of carrying a considerable load, has been found to be especially serviceable for packing and shipping purposes. If one of the boards or strips becomes broken in an ordinary box, the contents are liable to fall out, and in some instances the box will when partially broken soon fall entirely in pieces. A box made as herein described, however, cannot fall apart, should one of the panels or strips become split or broken, as the wires will bind it to the other strips and prevent it from becoming detached and lost.

The strips bound together by the wires form a fabric that can be shipped flat, and which may be formed into a box or other package. I prefer to bind the wires together between the slats (see Figs. 5 and 8) by a staple or wire 13 at the points where the corners are to be formed.

40 The details of the construction may be varied in many particulars without departing from my invention.

I claim as my invention:

1. A box having walls composed of a series of strips, a wire extending around the strips, and staples connecting the opposite leads of the wire through said strips and forming offsets or bends in the wire whereby it will be drawn taut around the strips and the edges of said strips will be drawn snugly together, for the purpose specified.

2. A box wall composed of a series of strips, a wire extending across the strips, and means for securing the several strips to said wire and forming offsets or bends in the wire to embed the wire in the strips and exert a tension on the wire to draw and hold together the edges of the strips, substantially as described.

60 3. A box wall composed of a series of strips, a wire extending across the strips, and staples extending across the wire and forced

into the body of the strips at points distant from the edges of the strips to form offsets in the wire embedding the strips remote from 65 their edges and exerting a tension on the wire to draw and hold together the edges of the strips, substantially as described.

4. A box composed of panels each made up of a series of comparatively narrow strips 70 having transverse grooves extending therein entirely around the panel, a wire fitting within said groove and having its ends interlocked at one edge of the panel, and staples passing through said strips and connecting 75 the opposite leads of said wire whereby it will be drawn taut around the panel and the edges of said strips will be drawn snugly together, substantially as described.

5. A box composed of panels made up of 80 comparatively narrow strips having transverse grooves near each end extending around the panel, wires fitting within said grooves and having their ends secured together, and staples passing through said 85 strips in the bottom of said grooves and connecting the opposite leads of the wires and binding them and the edges of said strips securely together, substantially as described.

6. A panel composed of a series of narrow strips placed edge to edge, wires extending along both sides of the panel and around the ends, and staples connecting the leads of the wires on opposite sides of the panel and forming when clenched or bent around the same 95 inwardly turned offsets or bends therein whereby the wires will be tightened between the ends of the panel and the edges of the strips will be drawn snugly together, substantially as described.

7. A panel composed of a series of comparatively thin wooden strips placed edge to edge and having transverse grooves on their surfaces on both sides extending from end to end of the panel, wires fitting within said 105 grooves and extending along both sides of the panel and around the ends thereof, and the ends of said wires being interlocked or secured together, and staples driven through said strips from side to side and straddling 110 the wires and having their ends bent or clenched around the wires on one side whereby offsets or bends will be formed in the wires and forced into the wood, and the wires will be tightened between the ends of the 115 panel and the edges of the strips drawn snugly together, substantially as described.

In witness whereof, I have hereunto set my hand this 7th day of March 1906.

ARTHUR O. HUBBARD.
